STEPBACK MECHANISM FOR PHONOGRAPH
TRANSCRIBERS

Lincoln Thompson, Cheshire, and Robert Leland Stone, Hamden, Conn., assignors to The Sound-
scriber Corporation, New Haven, Conn., a cor-
poration of Connecticut

Application April 17, 1941, Serial No. 388,956

8 Claims. (Cl. 274—14)

This invention relates to improvements in mechanisms for sound reproduction and more particularly to a stepback mechanism for a transcribing machine employing disc records.

The present invention is especially designed for dictating machines employing disc records of the type disclosed in Patent No. 2,200,866, issued May 14, 1940, to Lincoln Thompson, on an application filed December 15, 1938, Ser. No. 245,944, entitled "Disk dictating machine," and constitutes an improvement over the step-back mechanism disclosed in our copending application Ser. No. 248,691, filed December 31, 1938, entitled "Transcribing machine," patented April 29, 1941, No. 2,240,321.

In transcribing machines of the above nature, it is often desirable for the typist to play over a portion of the recorded dictation, and the present invention has for its principal object, the provision of an improved form of solenoid-operated "step-back" mechanism for back-spacing the pick-up needle a short distance over the record without raising the needle from or stopping the rotation of the turntable.

A further object is to provide means to brace the reproducing needle while the step-back action is taking place.

A further object is to provide a novel spring hinge connection between the pick-up unit and the arm carrying the same.

A still further object of this invention is to provide an improved form of step-back mechanism of the above nature which will be relatively inexpensive to manufacture, simple in construction, compact, ornamental in appearance, and very efficient and durable in use.

With these and other objects in view, which will appear as the description proceeds, there has been illustrated in the accompanying drawings one form in which the invention may be conveniently embodied in practice.

In the drawings:

Figure 1 is a perspective view of a transcribing machine embodying the features and principles of this invention.

Figure 2 is a top plan view on an enlarged scale of the improved step-back mechanism shown in cooperating relation with the reproducing pick-up carrying member.

Figure 3 is a side view of the same, looking in the direction of arrow 3 of Figure 2.

Figure 4 is a front view of a portion of the step-back mechanism, looking in the direction of arrow 4 in Figure 2.

Figure 5 is an enlarged fragmentary top view of a portion of the step-back mechanism illustrating by full and dotted lines three different operating positions of the same.

Figure 6 is a fragmentary side view partly in section of the sound reproducing unit and its carrying arm, and showing the appearance of spring hinge joint therebetween.

Figure 7 is an end view of the same.

Figure 8 is a schematic view of the invention including a diagram of the electrical circuits and control mechanism.

Referring now to the drawings wherein like reference numerals designate like parts throughout the several views, the numeral 10 denotes a casing over which a disc record supporting turntable 11 is adapted to rotate. The turntable 11 is arranged to be driven by an electric motor 12 (see Figure 8).

Provision is made of an arm 13 (see Figures 1, 2, 6, and 7), carrying a sound reproducing "pick-up" unit 14, which is hingedly secured thereto by a flat leaf spring 15, and also connected thereto by a coiled counter-balancing spring 16—said arm

13 being pivoted at 17 to the casing top 18 so as to swing over a thin disc record 19 carried by the turntable 11. The pick-up unit 14 carries a reproducing needle 20 which rides in the sound track previously formed on the surface of the record 19 by a dictating machine (not shown) and vibrates said pick-up unit 14, which is connected by conductors 21 and 22 to the input terminals of a vacuum tube amplifier 23 (see Figure 8). The output terminals of said amplifier 23 lead through conductors 24 and 25, to a loud-speaker or other sound reproducer, not shown.

As herein shown, the back-spacing or step-back means for the pick-up needle includes a flat frame plate 26 (see Figures 2, 3, 4, and 5), which is adapted to be adjustably secured upon the casing 10, or to any other suitable stationary part of the transcriber, as by a screw 27 extending through an elongated inclined slot 28 formed in said frame 26.

Mounted on the frame 26 is an electromagnet generally indicated by the numeral 29, having a sluggish U-shaped core 30, the upper leg 31 of which is surrounded by a wire coil 32. The magnet 29 is pivotally secured to the frame member 26 by a vertical screw pin 33 which passes through the upper leg 31 and lower leg 34 of the core 30 at a point adjacent the curved base of said core.

The coil 32 is adapted to be energized by electric current from a pair of wires L1 and L2 through conductors 35 and 36, under the control

of a switch 37, preferably hand or foot-operated, and located in circuit with said coil.

Provision is also made of a movable iron armature lever 38 of light weight which is pivoted to the end of the arm 31 as by a pin 39. The armature 38 is loosely mounted in a slot 40 provided in the free end of the leg 31, whereby said armature will be supported against lateral movement, and will be carried by the electromagnetic core 30 when the latter swings on its screw pivot pin 33. The armature 38 extends a short distance upwardly beyond the arm 31, and carries on its outer face, adjacent its upper end a pointed lug or knife-edge 41 which is adapted to engage with a side bar 48 on the pick-up arm to be described later.

In order to limit the swinging movement of the armature 38 in a direction away from the leg 34, provision is made of a stop finger 42 bent upwardly from the frame 26 into position to be engaged by the lower end of said armature 38, when the core 30 is not magnetized. A coiled tension spring 43 is connected at one end to a fixed angular post 44 preferably secured at one end to an upstanding ear 45 on the frame 26 by soldering, or brazing. The other end of the spring 43 is attached to the armature 38 at a point intermediate the upper and lower legs 31 and 34 of the core 30. The spring 43 thus serves to constantly urge the lower end of the armature 38 against the stop finger 42, and also acts to urge the electromagnetic core 30 toward the upturned frame ear 45 and into contact with a horizontal adjustable stop screw 46 which is screw-threaded through said ear 45 and is locked thereto by a lock nut 47.

The side bar 48 of the pick-up arm 13 is secured to said arm adjacent the rear end thereof as by rivets and said side arm extends into the path of the upper end of the armature 38 so that whenever the electromagnetic core 30 is magnetized by current passing through the coil 32, the knife-edge 41 will engage the curved edge 49 on the end of the side bar 48. The edge 49 is curved preferably on an arc struck from the center of the pivot 17 of the pick-up arm 13, so that when said pick-up arm 13 swings over the record 19, the curved edge 49 will at all times be equidistant from the knife edge 41.

In use, when the magnet 29 is energized, the armature or clapper 38, due mainly to its low inertia, will respond quickly to the attraction of the leg 34 of the core 30. The knife-edge 41 will thus engage the arcuate end of the side bar 48 with a "biting" action. Shortly, thereafter, the sluggish magnet core 30 will be caused to swing backwardly due to the attraction of a stationary iron post 50 which extends upwardly from the side of the frame plate 26 opposite to the side on which the stop screw 46 is disposed. The force due to the attraction between the legs 31 and 34 of the core 30 and the post 50 will cause the side bar 48 to back-space the pick-up arm any desired number of grooves according to the adjustment of the stop screw 46, it being understood that the needle will not be lifted from the record during this action.

The above described combined action of the armature 38 and the magnet core 30 is illustrated in Figure 5 wherein the initial position of the side bar 49 is shown in full lines, and its back-spaced position in dotted lines. It will be understood that upon energization of the coil 32 to magnetize the core member 30, the leg 34 of the magnet core 30 will attract the armature 38, which being relatively light in weight and low in

inertia, will be quickly swung about the pivot pin 33, causing the sharp point 51 of the knife-edge 41 to engage the curved end 48 of the thin side bar 48, as indicated at A in Figure 5. The relatively heavy core 30 will be slightly delayed in responding to the magnetic field but will be swung on its pivot screw 33 toward and against the armature post 50, as indicated in dotted lines at B in Figure 5, due to the magnetic attraction between the legs 31 and 34 of the core 30 and said iron post 50. The bar 49 will thus be caused to move from the full line position to the dotted line positions as shown in Figure 5. It will be clear from the above explanation that the knife-edge 41 will move in a somewhat angular path, first engaging the edge of the side bar 48, and then moving laterally with said side bar through the desired amount of back-spacing.

After the switch 37 is opened the armature 38 will be released from the magnetic attraction of the core 30 and will swing quickly due to the action of the spring 43 back into contact with the lug 42. The core 30 will then swing more sluggishly back to its original full line position, shown in Figure 5 in contact with the stop screw 46.

In order to brace and support the needle 20 against being bent when the pick-up 14 is stepped-back by the mechanism above described, provision is made of an angle block 52 secured to the underside of said pick-up, just behind the needle 20 (see Figure 7). The block 52 has a vertical arm 53 which is disposed closely adjacent to the reproducing needle 20, but not so close as to interfere with the normal vibrations thereof.

The pick-up used for the transcriber mechanism herein disclosed, should preferably be of the type disclosed in Patent No. 2,213,936, issued to Lincoln Thompson, wherein the needle movement is extremely flexible, the brace 52 being essential in order that the movements of the reproducer arm 13 should be transmitted to the needle 20 without excessive backlash, and yet permitting said needle to execute its normal vibrations without striking said brace 52. A further advantage of the use of the brace 52 is that the depending leg 53 will positively jar and vibrate the needle at each actuation so that it will never come to rest on the flat land between two adjacent grooves.

Operation

In operation, whenever the typist listening to the loudspeaker reproduction of the record 19 in response to the pick-up 14 desires to replay any desired portion of the record, it will only be necessary when this portion has been played to manually close the switch 37, which will be placed in a readily accessible position. The closing of the switch 37 will energize the coil 32, and thus magnetize the core 30, whereupon the light armature 38 will be quickly moved into engagement with the side arm 48. The heavy magnet core 30 will be more slowly swung about its pivot 33 and the combined action of the armature and core will cause the pick-up needle 20 to slide back over the record the determined number of grooves. If a greater number of grooves are to be replayed, the switch may be actuated two or more times in succession.

One advantage of the use of the flat leaf spring 15 to connect the arm 13 and pick-up 14, is that side play therebetween is almost entirely avoided, which is of utmost importance in producing an accurate and uniform amount of back-spacing every time the step-back mechanism is operated. This leaf spring also permits a pick-up head of

low inertia to oscillate vertically with a very low moment of inertia, thereby promoting tracking even though the record may be badly warped or bent.

If desired, the leaf spring 15 may be replaced by a flexible "packing" strip of rubberized fabric such as cotton, within the spirit and scope of the invention.

It will be understood that the step-back operation of the clapper 38 and the core 39 may be differentially adjusted by changing the air gap between the end of the clapper 38 and the member 42, as well as the air gap between the post 56 and the core 39. The tension and position of the spring 43 may also be changed if desired. The time and speed of each separate motion may thus be accurately controlled to produce any desired resultant effect. It will also be understood that the spring 43 may, if desired, be replaced by two separate springs at right angles to each other within the scope of the invention.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In a phonograph transcriber, a reproducer arm carrying a pick-up needle mounted to move with respect to the surface of a rotating disc record to be transcribed, a cam connected to said reproducer arm, and electromagnetically-operated means to engage said cam and move said reproducer arm rearwardly to step-back said needle a predetermined number of grooves without removing said needle from the surface of said record, said electromagnetically-operated means including a pivotally mounted slowly movable core of magnetic material and having a relatively high moment of inertia, a fixed iron post, a solenoid coil for magnetizing said core and causing said core to move toward said post, and a rapidly movable armature attracted by said core and having a knife edge engagement with said cam to clutch the latter and cause it to be moved rearwardly slowly with said core.

2. In a phonograph transcriber, a reproducer arm carrying a pick-up needle mounted to move with respect to the surface of a rotating disc record to be transcribed, a cam connected to said reproducer arm, electromagnetically-operated means to engage said cam and move said reproducer arm rearwardly to step-back said needle a predetermined number of grooves without removing said needle from the surface of said record, said electromagnetically-operated means including a pivotally mounted sluggish core of magnetic material and having a high moment of inertia, a fixed iron post, a solenoid coil for magnetizing said core and causing said core to move toward said post, and a rapidly movable armature pivoted to and attracted by said core, and having a knife-edge engagement with said cam to clutch the latter and cause it to be moved rearwardly slowly with said core.

3. In a phonograph transcriber, a reproducer arm carrying a pickup needle mounted to move with respect to the surface of a rotating grooved

sound record to be transcribed, an engagement member carried by said reproducer arm, electromagnetically-operated means to engage said member and move said arm rearwardly to step-back said needle a predetermined number of grooves, said means including a fixed iron post and a pivotally mounted slowly movable sluggish core of magnetic material having a high moment of inertia located adjacent said post and adapted when magnetized to be attracted to said post, a solenoid coil for magnetizing said core, a rapidly movable light weight armature pivoted to and attracted by said core when the latter is energized, said armature having a knife-edge for engaging said member to clutch it rapidly and cause it thereafter to be moved rearwardly relatively slowly with said core, and spring means to restore said armature and said core to their inactive initial positions when the magnetic flux is removed.

4. In a phonograph transcriber, a reproducer arm carrying a pickup needle mounted to swing with respect to a rotating disc record, said reproducer arm having a cam surface, a slowly-movable sluggish iron core having a solenoid coil mounted thereon, a rapidly-movable iron clutch lever pivoted to said core, a fixed armature post for attracting said core when said coil is energized, said clutch lever being more rapidly attracted by said core than said core is attracted by said post, whereby said cam surface will first be engaged by said clutch lever and thereafter moved more slowly by the swinging of said core to stepback said needle slowly a predetermined number of grooves, the axes of the pivots of said lever and said core being at right angles to each other.

5. In a phonograph transcriber of the type having a pivoted reproducing arm carrying a pickup needle which is mounted to swing across a rotating disc record, a fixed casing, said arm having a side extension provided with a cam edge concentric with the axis of said pivoted arm, a sluggish slow moving iron core pivotally mounted on said casing, an iron armature post fixed to said casing and adapted to attract said core when the latter is magnetized, a rapidly moving iron clutch clapper pivoted to said core and located in alignment with said cam edge, an electromagnetic coil surrounding said core for energizing it and causing said clutch clapper to swing quickly into engagement with said cam edge and thereafter cause said core and clapper to slowly move said arm to step-back said pickup needle a predetermined number of grooves.

6. In a phonograph transcriber, a casing, a disc record mounted to rotate on said casing, a pickup-carrying reproducer arm pivotally mounted to swing over said record, said arm having a side extension provided with a curved cam edge concentric with the pivotal axis of said arm, a relatively heavy sluggish iron core pivoted to said casing, a fixed iron post mounted on said casing and adapted to attract said core when the latter is magnetized, a relatively light iron clutch member pivoted to said core, an electromagnetic coil surrounding said core for magnetizing it and causing said clutch member to move rapidly into contact with said side extension, and to thereafter cause said core and the clutch member carried thereby to move more slowly to step-back said needle a predetermined number of grooves.

7. In a phonograph transcriber, a reproducer arm carrying a pickup needle mounted to swing

over a rotating disc record, said arm having a laterally extending cam surface, a slowly-movable sluggish iron core having a solenoid coil mounted thereon, a stationary iron post for attracting said core when said coil is energized, a rapidly-movable iron clutch lever pivoted to said core and adapted to be operated thereby, said lever having a knife-edge located in alignment with said cam surface, whereby when said coil is electrically energized said lever will be caused to clutch said cam surface quickly and thereafter to slowly step-back said needle-carrying arm across said record a predetermined number of grooves.

8. In a phonograph transcriber, a pivoted reproducer arm carrying an electric pick-up needle, said arm being mounted to swing with respect to the surface of a rotating grooved sound record to be transcribed, a lateral extension member

carried by said arm and having an engagement surface, a movably mounted clutch member in alignment with said engagement surface, and means to cause said clutch member to move in 5 a substantially square path in four successive steps from a starting position, including means for rapidly initially moving said clutch member against said surface for clutching engagement therewith; means for thereafter slowly swinging 10 said clutch member at right angles to backspace the needle-carrying arm a predetermined number of grooves; means for thereafter quickly moving said clutch member out of contact with said engagement surface; and means for thereafter slowly moving said clutch member at right angles back to the starting point.

LINCOLN THOMPSON.
ROBERT L. STONE.
